CLAIM

The ornamental design for a combined closure for medical bottle and safety cap therefor, substantially as shown and described.

DESCRIPTION

FIG. 1 is a side elevational view of a combined closure for medicine bottle and safety cap therefor, showing our new design;

FIG. 2 is a side elevational view of the closure member of FIG. 1;

FIG. 3 is a side elevational view of the safety cap member of FIG. 1;

FIG. 4 is a top plan view of the closure member of FIG. 1;

FIG. 5 is a bottom plan view thereof;

FIG. 6 is a top plan view of the safety cap of FIG. 1;

FIG. 7 is a bottom plan view thereof; and

FIG. 8 is a bottom exploded perspective view of the closure member and safety cap member of FIG. 1. The closure member and safety cap member respectively are shown separately for clarity of illustration in FIGS. 2-7 inclusive.
